(57) **CLAIM**

The ornamental design for a combined speech aid and base for tracheostomy and laryngectomy patients, as shown and described.

DESCRIPTION

FIG. 1 is a front view of a speech aid member of a combined speech aid and base for tracheostomy and laryngectomy patients;

FIG. 2 is a right side view thereof;

FIG. 3 is a left side view thereof;

FIG. 4 is a rear view thereof;

FIG. 5 is a top view thereof;

FIG. 6 is a bottom view thereof;

FIG. 7 is a front view of a base member of a combined speech aid and base for tracheostomy and laryngectomy patients;

FIG. 8 is a left side view thereof;

FIG. 9 is a right side view thereof;

FIG. 10 is a rear view thereof;

FIG. 11 is a top view thereof;

FIG. 12 is a bottom view thereof;

FIG. 13 is a perspective view thereof, shown in an environment of use;

FIG. 14 is a front view of a combined speech aid and base for tracheostomy and laryngectomy patients;

FIG. 15 is a left side view thereof;

FIG. 16 is a right side view thereof;

FIG. 17 is a rear view thereof;

FIG. 18 is a top view thereof;

FIG. 19 is a perspective view thereof; and,

FIG. 20 is another perspective view thereof.

The broken lines showing the rechargeable battery in FIG. 13 represent the environment. Other broken lines in the drawing views are included for the purpose of illustrating portions of the combined speech aid and base for tracheostomy and laryngectomy patients that form no part of the claimed design. None of the broken lines form a part of the claimed design.
